18 Claims.

(Cl. 194—7)

The present invention relates to apparatus for providing a paper cover for toilet-seats. A means is provided whereby a roll of paper is pulled across the top of the toilet-seat from one side of same to the other. The means used for accomplishing this purpose comprises apparatus actuated by an electric motor, and which is controlled by the use of a coin deposited in said apparatus. Once the coin is deposited in the actuating 10 apparatus, a fresh sheet of paper is pulled from the roll located on one side of the toilet-seat into proper position over the latter for use, and synchronously therewith a part of the roll on the opposite side of the toilet-seat is wound up to 15 accomplish the object in hand. The exact means of accomplishing this will be described herein-after in this specification.

Another object of the invention is to automatically remove the sheet of paper after it has been 20 used, by mere automatic action of the toilet-seat itself, and at the same time uncover the latter so that there is no sanitary protection on the seat when same is not in use. This feature will also be described hereinafter.

25 The motor operating the device is also by slight mechanical alterations designed to be put into operation by the use of various denominations and sizes of coins, such as a cent, a nickel, ten cent piece etc., as desired.

30 The invention in hand is adapted to be used in connection with the currently used type of toilet seat, as well as with those specially designed for use in connection with the present invention.

Other features of the invention will appear as 35 the description proceeds herein.

In the accompanying drawings forming part of the present specification, I have illustrated a complete embodiment of my invention constructed according to the best means I have so far devised for the practical application of the principles of my invention in which:

Figure 1 is a top plan view of a toilet-seat with my invention applied thereto.

Figure 2 is an end elevation of the invention 45 taken from the right of Figure 1.

Figure 3 is an end elevation, partly in section, taken from the left of Figure 1.

Figure 4 is a top plan view of the coin actuated apparatus and associated parts used in my invention, the cover of which is removed for illustration purposes.

Figure 5 is a rear elevation of the device shown in Figure 4.

Figure 6 is a transverse section on lines 5—6 55 of Figure 5.

Figure 7 is a vertical section taken on line 7—7 of Figure 4.

Figure 8 is a vertical transverse section through a portion of the device which is actuated by a coin and is taken on the line 8—8 of Figure 4.

Figure 9 is a vertical transverse section taken on line 9—9 of Figure 8.

Figure 10 is a transverse section on line 10—10 of Figure 8.

Figure 11 is an enlarged detail section of a portion of the device taken on line 11—11 of Figure 12.

Figure 12 is an enlarged elevation of a portion of the device partly in section, taken on line 12—12 of Figure 4.

Figure 13 is an enlarged detail of the end of one of the rollers used in my invention, taken on line 13—13 of Figure 12.

Figure 14 is an enlarged detail section taken on line 14—14 of Figure 1.

Figure 15 is a plan view of my invention illustrative of the roll of paper used.

Figure 16 is a plan view showing the successive portions of the paper roll used.

Figure 17 is a longitudinal section on line 17—17 of Figure 16.

Figure 18 is an electrical wiring diagram used with my invention.

Figure 19 is a transverse view taken on line 19—19 of Figure 4.

Figure 20 is an elevation of a portion of the toilet-seat lid taken on line 20—20 of Figure 22.

Figure 21 is a side view, partly in section, of Figure 20 taken from the left side thereof.

Figure 22 is a transverse section, taken on line 22—22 of Figure 1.

In the drawings, the numeral 1 indicates a toilet-seat having the customary opening 2 therein, same being hinged at points 3, 3 on the rod 4. The rod 4 is mounted on the standards 5, 5 which are rigidly mounted on the support 6 of the toilet-bowl.

Covering the toilet-seat 1 is a thin sheet of metal 7 having an aperture therein 8 of larger diameter than the opening of the toilet-seat. 45 This sheet of metal 7 is hinged by means of the metal tubing 9, 9 on the rod 4 as shown, so that the metal sheet may be lifted upwards as well as the toilet-seat 1 about the pintle or rod 4.

On each end of the metal sheet 7 is mounted 50 a metal cylinder 10, 11 in which is enclosed a roll of paper. The nature of this roll of paper is illustrated clearly in Figures 15 to 17, in which it is seen that two opposed and continuous strips of tape 12, 12 are mounted on periodically spaced 55

sheets of paper 13, 14 etc. The paper sheets 13, 14 are provided with the aperture 8 before mentioned and also with a plurality of small openings 15, 16 etc., best illustrated in Figure 16 of the drawings. As the sheets of paper 13, 14 are in stressed relation to each other on the tapes 12, 12, it is seen that an aperture 17 is between each successive sheet 13, 14 of the roll of paper. The purpose of the apertures 15, 16, 17 will be described hereinafter.

From Figures 1 and 14 of the drawings is seen the nature of the support 18 used for the roll of paper 19 at one end of the device. In Figure 14 it is seen the roll of paper 19 is mounted on a roller 18, which in turn is mounted in the metal enclosing cylinder 11 by means of the pintle 28. It is seen that the paper roll may be withdrawn from the enclosing cylinder 11 over the top of the metal sheet 7 and wound within the enclosing cylinder 10 when said paper is properly actuated, as will be described hereunder. A rod 21 is revolvably mounted in the end walls 22, 23 of the enclosed cylinder 11. On said rod 21 are rigidly mounted a pair of fingers 24, 24 the shape 25 of which is clearly shown in Figures 1, 4, 14, and their purpose will be described herein. In order to enable the roll 19 to be smoothly unwound over the part 25 of the surface 26 of the metal sheet 7, a holder 27 shown in Figure 14 is used 30 in the cylinder 11. This holder 27 is mounted at 28 adjacent to the hinge 29 of the metal cylinder 11. One holder 27 is used on each end of the cylinder 11 for this purpose. In the enclosing cylinder 10 is mounted a roller 30 somewhat similar to roller 18 except that at the end 31 which is adjacent to the actuating apparatus 32, a slot 33 is formed in the end of the roller 30 and operates as clearly illustrated in Figure 12. The actuating mechanism which revolves the roller 30 and winds the paper 35 from the cylinder 11 into the cylinder 10 is shown in Fig. 12 and will next be described.

This apparatus which is illustrated in Figures 4 to 7 inclusive comprises a multiplicity of parts 45 such as an electric motor 31, an electro-magnet 38 with its armature 39, a coin box 40, a worm 41, and its gear 42, an electric switch 43 and other parts described in detail as follows:

A metal plate 44 is mounted on the metal sheet 50 7 at 45, Figure 1. On this plate 44 is supported by means of the metal band 46, the electric motor 31. The stem 47 of the motor carries the worm 41 and a horizontally disposed disc 48, both of which revolve with said stem. A pintle 49 is rigidly mounted in the metal plate 44. On this pintle 49 is rigidly mounted the worm gear 42, which is in meshed engagement with the worm 41 so that when the motor operates the worm gear is revolved, and with it the pintle 49.

60 In Figure 12 it is seen that the end 34 of the pintle or axle 49 is provided with two outstanding opposed lugs 50, 50 which are in engagement with the slot 33 in the end of the roller 30 which carries a roll of paper before described. Thus 65 the operation of the motor will roll the paper from the enclosing cylinder 11 into the enclosing cylinder 10. Surrounding the pintle 49 is a fixed sleeve 51, in which the pintle revolves, said sleeve 51 being rigidly mounted in the metal plate 44 at 52, Figure 12. The hollow sleeve 51 has an inset portion 53 on which revolves the drum or thimble 54. On the thimble 54 are mounted a smaller and a larger disc 55 and 56 respectively, having 70 a channelway 57 between them; the larger disc 75

56 has a slot 58 formed therein as shown clearly in Figure 11, and revolves freely on drum 54.

A pin 59 having a head 60 is rigidly mounted in the worm gear 42, said pin operating in the slot 58. On the larger disc are rigidly mounted on 5 the side thereof a pair of pointed bars 61, 62 the purpose of which will be described below. In the channelway 57 is mounted a light spring 63 which surrounds the drum 54, one end of said spring being attached to the pin 59 at 64, and 10 the opposite end secured to the large disc 56 at point 65, so that when the pointed bars 61, 62 are turned in a clockwise direction as seen in Figure 11, it meets the resistance of said spring, which tends to throw them in an opposite direction. 15 On the pintle 49 a spring 66 is mounted which bears against the cotter pin 67 at one end, and against the Z-shaped part 68 at the other. The action of this spring tends to keep the worm gear, the sleeve 51 and associated parts in position, and the pintle 49 in engagement with the slot 33 in the end of the roller 30, but the outer end of the pintle 49 may be withdrawn manually to permit removal of the roller 30 as is readily understood.

25 Mounted on the metal plate 44 is an angular support 69, which carries a switch-box 70. The switch-box has a pivoted arm 71 which is actuated by a sliding rod 72 by means of an outwardly turned extending pin 73 mounted on the latter. Within the switch-box 70 is an electric switch 43, Figure 18, which when closed permits electric current to flow from the wire 130 to the wire 147, the movement of the sliding rod 72 to the right pulling the outstanding pin 73 with it 30 and closing the switch 43. The slideable rod 72 is mounted on the metal plate 44 by means of the two brackets 76, 77. The slideable rod 72 is provided with a downwardly turned end 78, and a pair of opposed extensions 79, 80. Said rod 72 35 has a spring 81, one end of which abuts against the washer 82 and the other end against the outstanding flange of the bracket 77. The tendency of this spring is to push the slideable rod 72 as far to the left as possible and the limit of its travel 40 is governed by the position of the bent plate 95, which abuts against the pin 96 mounted in the metal plate 44. An operating rod 83 which runs parallel with the metal plate 44 is attached at one end to the extension 79 and on its opposite end 45 connects pivotally with the transverse rod 21 by means of an upstanding connecting rod 84 as shown in Figures 4 and 5 of the drawings. This rod 83 is operated by the movement of the slideable rod 72 and revolves the transverse rod 21 50 when the rod 72 is properly actuated, to raise and lower the fingers 24, 24 mounted on the rod 21.

55 Also mounted on the metal plate 44 by means of a bracket 85 is the electro-magnet 38, which has the usual windings 86, a core 87, and a pivoted armature 39, which is hinged at 90 to an extension of the core 87. The upper end of the armature 39 engages the extension 80 on the slideable rod 72 and it is seen that when the armature 39 is pulled to the right (Figs. 4 and 5) by the operation of the electro-magnet 38, that the said extension 80 pulls the slideable rod 83, and the pivoted arm 71 of the electric-switch 43.

60 The paper 35 used in connection with the device illustrated in Figures 16 and 17 of the drawings as before mentioned is provided with the apertures 15 and 16 and the fingers 24, 24 which are mounted on the transverse rod 21 are normally in engagement with the pair of apertures 70 75

16, 16 etc., and when the transverse rod rotates on its axis by means of the operating rod 83, the said fingers 24, 24 are raised out of engagement with the said apertures as is readily understood, 5 thus permitting the roll of paper contained in the enclosing cylinder 11 to be pulled to the right, as seen in Figure 1. The roll of paper contained in the enclosing cylinder 10, which is mounted on the roller 30, as before explained, may be revolved by means of the worm 41 and worm gear 42 and the pintle 49, as clearly illustrated in Figure 12 of the drawings. Thus it is seen that when the motor 37 operates and a current of electricity is passing through the electro-magnet 38 and 10 the armature 39 operated to the right as seen in Figure 5, thus raising the fingers 24, 24, the paper 35 is operated to the right as shown in Figure 1. When the electric circuit is broken which passes through the electro-magnet 38, a spring 81 on the 15 slideable rod 72 tends to push the latter to the left and the fingers 24, 24 will then re-engage in the holes 15, 15 of the paper 35. Mounted on the metal plate 44 is an outstanding pintle 91. This pintle carries a revolvable sleeve 94, which has rigidly mounted on its outer 20 extremity an L-shaped member 92 and an outstanding bracket 93 also rigidly mounted on the sleeve 94. Both the L-shaped member and the bracket are revolvable on said pintle when the L-shaped member is in engagement with the pointed bar 61 or 62 carried by the large disc 56, shown in Figures 11 and 12 clearly; the purpose of the L-shaped member will be described below. 25 Also rigidly mounted on the sleeve 94 is a bent plate 95 and it is seen that this plate which bears against a pin 96 carried by the metal plate 44 acts as a stop for the revolution of the said sleeve 94 as will be further explained. A pin 97 is mounted in the metal plate 44 and carries on its outer end a spring 98, the lower end of which is attached to the outstanding flange of the bracket 93. When the bracket 93 is in normal position the lower end of the spring 98 tends to hold the bent plate 95 against the pin 96 but 30 when the pointed bars 61 or 62, Figure 11, revolve and engage the L-shaped member 92 the strength of said spring is overcome and the L-shaped member 92 rotates in a clockwise direction as same is seen in Figure 5 of the drawings. 35 A pintle 99 is rigidly mounted on the metal plate 44 and carries on its outer end a U-shaped brake-shoe 100 by means of a depending member 101 which is pivotally connected at 102 to the brake-shoe, as clearly illustrated in Figure 7. On the 40 right end of the brakeshoe, as shown in Figure 5, a connecting link-bar 103 is pivotally attached at 104 Figure 11, said bar being also pivotally connected with the armature 39 of the electro-magnet 38. It is evident that when the armature 39 is operated to the left (Figure 5) the brakeshoe will bear on the upper surface of the disc 48 mounted on the stem 47 of the electric motor 37, and due to the depending member 101 will exert a braking force on the disc 48 and tend to bring the motor to a complete positive stop when the electric current is shut off from the motor. 45

A Z-shaped member 68 is mounted on the metal plate 44 and carries on its upper end a fuse holder 105, and a fuse 106 which is of service in connection with the electric current carrying system in the device as will be explained below. 50

The coin-actuated mechanism will now be described which comprises the following parts: A pair of opposed side walls 107, 108 of insulating

material form a chamber 109, as clearly shown in Figures 8 to 10 and 19 of the drawings. A pintle 110 revolvably mounted in side wall 108 carries rigidly mounted thereon a short arm 111, and a second pintle 112 revolvably mounted in wall 108 carries another short arm 113 rigidly mounted thereon. Opposite to these arms 111 and 113 is a metal part or guide 114, rigidly mounted in the insulated part 115 between the side walls 107 and 108. Adjacent to guide bar 114 and electrically connected therewith is the rigidly mounted pintle 146, from which proceeds the wire 124. A coin 122a is shown in Figure 8 as engaged between the arm 113 and the guide bar 114. In the walls 107 and 108 is revolvably mounted the longitudinal actuating rod 116, the other end of which is carried revolvably in the wall 117 (Figs. 4 and 5). A flat bar 118 is slidably mounted between the two walls 107, 108 (Figs. 8, 9 and 5) in a groove 119, and the downwardly turned end 150 of said bar engages in the rectangular loop 120. A flat spring 121, mounted on the bolt 149 engages against the downwardly turned end 150 of bar 118, tending to hold same in its extreme position to the left as seen in Figure 8. When the loop 120 of rod 116 is turned to the right (Figure 8) the bar 118 is withdrawn to the right and permits a coin to pass through passage 151, and fall on arm 113 and be held in position against the guide bar 114. A coin 122 may also be held by arm 111 in position (Figure 8) and when said arm is turned to the right the coin will fall on the bar 118. When the bar 118 is withdrawn, the coin will take position 122a just described; and when arm 113 is turned to the right, the coin will fall down chute 151 to the coin box 40 (Fig. 7) as is at once understood. On the exterior of the side-wall 108 is located the following apparatus: A pivoted lever 152 of insulating material is mounted in the side-wall 108 near the top thereof at the point 153, and carries a downwardly projecting rod 154, rigidly mounted therein. A short connecting rod 155 connects the lever 152 with a short lever 156, which is mounted in the wall 108 on the end of the pintle 110 before described. A connecting rod 157 connects the end of the short lever 156 with the lever 158 which is carried on the end of pintle 112 before mentioned herein. On the wall 108 is rigidly mounted at 158a the coil spring 159, the lower end of which engages against the end of lever 158. It is evident that due to the pressure of spring 159 the levers 158, 156 and 152 are all normally held in their lowest positions as seen in Fig. 19, and accordingly the arms 111 and 113 are held normally in their extreme positions towards the left as seen in Fig. 8 ready to receive a coin and prevent its passage through the channel 151 before described, until and unless the levers just named are operated by means of the rod 154 being moved to the left as seen in Fig. 19 by the L-shaped member 92 shown in Figs. 4 and 5, as is at once understood. Connected to the pintles 110 and 112 are the two electric wires 145 and 148 respectively carrying electric current from said pintles. Also the pintle 146 before mentioned carries an electric wire 124. The said wires 145, 148 and 124 will be further described herein. It is also noted the coin actuated device as a whole just described is mounted by means of the brackets 155a, 156a on the plate 44. From Figures 1, 4, 5, 20, 21, 22 it is seen that the longitudinal rod 116 mounted in wall 117 of the coin actuated mechanism is connected with 75

a rod 157a which passes into the liftable toilet-seat 1, and is attached to the small lever 158b located therein, and pivoted at 159a. When the seat 1 is depressed as seen in Figure 22, the lever 158b operates the rod 157a which in turn operates the rod 116, the loop 120 thereon and the slidable bar 118, Fig. 8, and withdraws said bar to permit a coin to pass downward through passage 151 as will be further described below under the "operation" of the whole invention.

It will also be seen the wire 145 (Fig. 18) extends to the spring-operated switch 142 (Fig. 21) and when the toilet-seat 1 is depressed the button 160 opens the switch 142 by lifting the flat spring 161 from the terminal 143 in the toilet-seat, thereby electrically disconnecting the wire 145 from the wire 134. It is further observed that the seat 1 is normally held off the part 162 by means of spring 163 and this permits the spring 164 to hold the pivotal lever 158b in its lowest position as shown in Fig. 21, and in this position the loop 120 on rod 116 permits the spring 121 to hold the slidable bar 118 in its extreme left position (Fig. 8) and normally to prevent a coin passing through the channel 151.

When the seat 1 is forced downward on top of the part 162, the lever 158b is depressed, the spring 164 overcomes, the rod 157a pulled inward toward the plate 44 (as seen in Fig. 4) and the loop 120 on rod 116 is thereby forced to the right as seen in Fig. 8 and the slidable bar 118 thereby withdrawn from the channel 151 which permits a coin to pass downward by said bar and occupy position 122a.

The invention in hand is furnished with a suitable electric wiring system, the parts of which may readily be understood from the description setting out the path of the electric currents used in the device, as follows:

One circuit operates the electro-magnet 38 and the other circuit operates the motor 37. The electro-magnet circuit may be traced as follows from the diagram Fig. 18:—

The current enters through the source of electric power, through the wire 126 to point 128; thence by wire 140 to point 139 on the electro-magnet; thence through the magnet to point 138 thereon; thence by the wire 124 to and through the pindle 146; thence through the coin 122 to point 137; thence by the wire 145 to point 143 of the switch 142; thence by wire 134 to point 135 on the fuse 106 thence to point 141; thence by wire 127 to the source of power.

The motor circuit may be traced as follows on the diagram Fig. 18:—

The current comes in by wire 126 to point 128; thence through the motor 37 to point 129; thence by wire 130 to point 132 at the switch 43; thence to point 133 and by wire 147 to junction point 144; thence by wire 145 to point 143 on the switch 142; thence by wire 134 to point 135 on the fuse 106 through point 141 and wire 127 to the source of power.

There is still a third circuit which operates the electro-magnet 38 as follows:—

The current comes in by wire 126 to point 128; thence by wire 140 as before described to the electro-magnet 38; thence by wire 124 to the pindle 146 and through the coin 122a; thence by the wire 148 to the wire 147, to junction point 144 and thence by wire 145 to point 143 on the switch 142, through the switch and by wire 134 to and through the fuse 106 and thence by wire 127 to the point of electric supply. It will be noted that the coin 122 is released after a time

and falls to the position 122a, so that the two currents which connect through the coins only operate one at a time.

Operation

The procedure followed in operating the above invention is as follows:—

When the device in hand is not in use the toilet-seat 1 has the aperture 17 (Fig. 16) in position over the top of the toilet-seat, only the two portions of tape 12, 12 extending over the top of the exposed portion of the toilet-seat 1. A suitable coin such as 122 Fig. 8 is dropped in the slot 165 which leads to the channel 151 and said coin is caught between the arm 111 and the guide bar 114, forming an electrical connection between the said two last named parts. When this is done the electro-magnet circuit described in connection with Fig. 18 is at once energized. This causes the armature 39 to be drawn to the core 47 of the electro-magnet 38, by which action the sliding rod 72 overcomes the spring 81 and draws the operating rod 83 to the right as seen in Figs. 4 and 5 of the drawings. This action in turn operates the transverse rod 21, in cylinder 41, and lifts the fingers 24, 24 out of the apertures 15, 15 of the roll of paper 35, thus permitting said roll to be advanced across the seat and into the cylinder 40 which encloses the roller 30 as soon as the latter is revolved by means of the pindle 49 which carries the worm gear 42. As soon as the fingers 24, 24 are lifted and the roller 30 begins to revolve (as will be described) the said fingers are held in a raised position, due to their resting on the upper surface of the paper 35 which is on the roll in the cylinder 41, and this being the case, the armature is held against the electro-magnet core until such time as the roll of paper 35 is advanced to a point where the fingers can fall in the next set of apertures 16, 46. When the sliding rod 72 is in the position just described, by means of the outstanding pin 73, the arm 71 controlling the switch 43 is operated to the right as shown in Figs. 4 and 5. When this is done, the motor electric circuit begins operation, the motor 37 begins to revolve, and operates the worm 41, the worm gear 42, the pindle 49, which in turn by means of the inner end 34 of same begins to operate the roller 30 in the enclosing cylinder 40. The roll of paper 35 then begins to advance over the toilet-seat 1, as is at once understood.

As the pindle 49 revolves, the pointed bars 61, 62 remain stationary for a certain period of time, depending on the length of the slot 58 in the disc 56. Once the pin 59 reaches the end of the said slot 58 the bars 61 and 62 are advanced with the rotation of the pindle 49, due to the pin 59 being mounted in the worm gear 42. This length of time is adapted by means of the slot 58 in disc 56 to be long enough to prevent the fingers 24, 24 which have been raised by the action of the operating rod 83 from dropping back into the said apertures 15, 15 of the paper roll 35. When either one of the pointed bars 61 or 62 advances in a rotary direction, they engage the bracket 93 on the end of the pindle 49 and overcome the strength of the spring 98 and push the L shaped member 92 downwardly, and into engagement with the rod 154 of the coin-actuated apparatus 70 and throw said rod to the left as seen in Fig. 19 of the drawings. This action overcomes the strength of the coil spring 159 and turns the pintles 110 and 112 on their axes and with them their respective arms 111, 113 Fig. 8. When this

takes place, the coin 122 drops down the channel 151 and rests on the end of the slideable bar 118. As soon as the coin 122 breaks the electric connection between the arm 111 and the guide bar 114, it is seen the electro-magnet circuit, which energizes the electro-magnet 38, is broken, in which case the sliding rod 72 is forced to the left as seen in Fig. 5, (since the fingers 24, 24 on the transverse rod 21 have simultaneously therewith reached the second set of slots 16, 16 in the paper roll 35 thus permitting spring 81 to act,) and by means of the automatic action of spring 81 the current passing through switch 43 is broken and this in turn being in the motor circuit, immediately stops the motor from further operating or advancing the paper roll 35 by means of the roll 30. It will be observed that during the period of the above operation of the two electric currents, that the switch 142 in the toilet-seat 1 has been closed, permitting the current to flow therethrough. The weight on the toilet-seat when the device is in use, then pushes downward the toilet-seat 1 on top of the part 162 and this action operates button 160 and breaks the electrical connection through switch 142, and at the same time pulls the rod 157a inwardly toward the toilet-seat as seen in Fig. 1, and this action in turn withdraws the bar 118 from the channel 151 of the coin-actuated apparatus as before described, and permits the coin 122 to fall into position, shown as at 122a and held by the arm 113 and the guide bar 114 and making an electrical connection between the said last two named parts. However, as the switch 35 142 is open as long as the toilet-seat 1 is depressed, the electro-magnet circuit cannot operate even though the coin 122a is an electrically working circuit.

Immediately the person using the toilet-seat 1 rises, the switch 142 comes into operation due to the button 160 having the pressure removed therefrom and the spring 164 Fig. 21 again pushes the lever 158b downward and the spring 121 Fig. 8 returns the slideable bar 118 to its normal position. As soon as the switch 142 is closed, the electro-magnet circuit begins to operate the second time, the armature 39 is again drawn to the right (Fig. 5) the sliding rod 72 operates to pull the switch arm 71 to the right and closes the motor circuit a second time. The motor begins at once to operate as before described and revolves the roller 30 a second time, thus advancing the roll of paper 35 across the top of the toilet-seat 1 until the used portion of the paper which has been on the toilet-seat is entirely wound upon the roller 30 in the cylinder 10, leaving only the apertured space 17 on top of the toilet-seat. The purpose of this action if of course to uncover the toilet-seat so that a new user of the device has to place another coin in the coin actuated apparatus before the device will operate.

After the motor has run a second time for a predetermined period depending on the length of the slot 58 in the disc 56, one of the pointed bars 61 or 62 again engages the bracket 93 on the pintle 91, the L shaped member 92 is lowered, engages the rod 154 at which time the arm 113 Fig. 9 releases the coin 122a which falls into the coin box 40 and the electro-magnet circuit is again broken, which in turn breaks the connection at switch 43 thus stopping the motor and with it the further winding of the paper on the roller 30. At this time the fingers 24, 24 have reached 75 a new set of apertures corresponding to 16, 16 in

the roll of paper 35, and the spring 81 is thus permitted to push the sliding rod 72 to its normal position against the bent plate 95, which acts in conjunction with the pin 96 as a stop for said rod. It is also observed that as soon as the pointed bar 61 or 62 rotates sufficiently to free itself from the bracket 93, the spring 98 returns the said bracket and the L shaped member 92 to their normal position. It should be stated further that as soon as the weight is removed from the toilet-seat 1, the spring 163 pushes the seat upward to its normal position off the part 162, which enables the button 160 to be pushed downward as seen in Fig. 21 and the spring 164 to push the lever 158b out into its normal position. There is a cover (not shown) for the actuating mechanism which encloses same, so that the said mechanism is kept free from being tampered with by the public and this cover also closes in the coin box 40 as is readily understood.

In connection with the positive stopping of the motor when the electrical currents are cut off at any period of its operation it will be noted that the armature 39 operates the depending member 101, which reacts against the pintle 99 on which it is mounted, to engage the brakeshoe 100 firmly against the disc 48 which is rigidly mounted on the stem 47 of the motor 37 and brings the motor to a positive and quick stop, thereby overcoming any momentum which the motor might have after the electric currents have been shut off.

It is to be noted in the above described operation of the device that when the armature circuit is energized and the armature 39 drawn to the core 87 of the magnet by electrical influence and the switch 43 of the motor circuit is in correspondence therewith closed, the motor begins to run. As soon as the motor runs a very short time, governed by the length of the annular slot 58 in the disc 56 the pointed bars 61 or 62 act on the bracket 93 controlling the L-shaped member 92 and release the coin 122 as above described, from the arm 114, the magnet circuit is broken by the release of said coin and such circuit ceases to operate. Nevertheless the motor continues to run thereafter as long as the switch 43 is held to the right as seen in Fig. 5, and such switch is held in such position for a period of time governed by the distance between the succeeding slots 15 and 16 in the roll of paper 35 for the reason that while the fingers 24, 24 ride on the top surface of the paper they still hold the operating rod 83 to the right and prevent the sliding rod disconnecting the switch 43 until such time as the fingers 24, 24 reach the pair of slots 16, 16 in which case the operating rod 83 is released and the spring 81 thereon then acts to push the sliding rod 73 to the left, thereby opening the switch 43 and breaking the motor circuit and stopping the motor.

I claim:

1. In an actuating mechanism for operating a device of the class described, an electro-magnet, having a core, a hinged armature mounted on the magnet core, a motor having a central pintle, a worm on the pintle, a worm gear having a pintle therethrough, an electric switch and electric circuit for operating the motor, a coin-actuated mechanism electrically connected with the magnet, a longitudinal sliding rod having a downward extension in engagement with the armature, a spring for holding the said sliding rod in normal position, a revolvably mounted L-shaped member adapted to operate the coin-ac-

tuated mechanism, means on the worm-gear pintle for revolving the L shaped member, and means on the longitudinal sliding rod for operating the switch of the motor circuit.

5 2. In a device of the class described having a liftable toilet-seat and support therefor, a roll of paper adapted to be drawn from one side of the toilet-seat to the other, means for advancing the said roll of paper across the toilet-seat comprising: an electro-magnet having a core, a hinged armature mounted on the magnet core, a motor having a central pintle, a worm on the pintle, a worm-gear having a pintle therethrough, an electric switch and an electric circuit for operating the motor, a coin-actuated mechanism electrically connected with the magnet, a longitudinal sliding rod having a downward extension in engagement with the armature, a spring for holding the said sliding rod in normal position, a revolvably mounted L shaped member adapted to operate the coin-actuating mechanism, means on the worm-gear pintle for revolving the L shaped member, means on the longitudinal sliding rod for operating the switch of the motor circuit, and means for starting the electro-magnet mounted on the toilet-seat, actuated by the motion of the toilet-seat, when lifted from its support.

3. In a device of the class described, a coin actuated mechanism comprising a supporting metal plate, a pair of spaced-apart insulated side walls, having a coin-shute formed therebetween, mounted on said metal plate, a top lever, pivotally mounted in said side-walls, a downwardly projecting rod mounted in said pivoted lever, an intermediate short lever, pivotally mounted in one of the side walls, a connecting rod between the two foregoing levers, a bottom lever mounted in one of the side walls, a connecting rod between the short lever and the bottom lever, a coil spring rigidly mounted on one of the side walls and bearing against the free end of the bottom lever, and tending to hold the latter in normal position, a pair of coin holding arms located within the shute mounted on the pintles of the intermediate and bottom levers respectively, a guide bar positioned between the side-walls and in the said shute, a pintle passing through one side wall adjacent to the guide bar, a slidable bar adapted to reciprocate between the side walls, an operating rod mounted in the said side walls in engagement with the end of the slidable bar, a spring mounted in the side-walls adapted to hold said bar in its innermost projecting position in the said shute, means adapted to engage the downwardly projecting rod and the coin holding arms for the purpose of releasing the coin held in said shute, and means for revolving the operating rod and permitting the flat bar to be reciprocated to a position which permits the passage of a coin through said shute.

4. In a device of the class described, comprising a toilet-seat, metal seat-cover therefor, a roll of paper adapted to slide over the metal seat-cover of the toilet seat, having a pair of opposed apertures therethrough, and spaced periodically therein, a roller on one side of the toilet-seat on which the roll of paper is mounted, a second roller mounted on the opposite side of the toilet-seat for drawing the roll of paper forward, a power actuating mechanism for revolving the last named roller, a coin-actuated mechanism for starting said actuating mechanism, an electro-magnet electric circuit, and a motor electric circuit, a transverse rod mounted near the first named

paper supporting roller, a pair of fingers mounted on said transverse rod normally in engagement with a pair of opposed apertures in the roll of paper, a longitudinal operating rod connected to the actuating mechanism, a connecting rod connecting said operating rod with said transverse rod adjacent to the roller, means mounted in the toilet-seat for starting the electro-magnet electric circuit and means in said seat for mechanically releasing a coin in the coin-actuated mechanism.

5 5. A device of the class described, comprising a toilet-seat, a metal seat-cover therefor, a roll of paper adapted to slide over the metal seat-cover having alternately therein open spaces, and portions of paper having successive pairs of opposed small apertures therein, a pair of opposed strips of tape mounted on the roll providing a means of drawing the roll across the toilet-seat, a roller on one side of the toilet-seat on which the roll of paper is primarily mounted, a second roller mounted on the other side of the toilet-seat for drawing the roll of paper forward thereto, a power actuating mechanism for revolving the last named roller, having an operating rod 25 projecting therefrom, a motor circuit and an electro-magnet circuit for the power actuating mechanism, a coin-actuated mechanism adapted to operate the magnet circuit, an enclosing cylinder mounted on the metal seat-cover enclosing the pulling roller for the paper roll, a transverse rod revolvably mounted in the last named enclosing cylinder, a connecting rod mounted on the transverse rod and connected to the operating rod, means for holding the switch of the motor 30 circuit in operating position after the magnet circuit is broken, comprising a pair of fingers on the said transverse rod adapted to ride on the surface of the paper roll while same is being drawn forward across the toilet-seat, and adapted to engage in the small apertures of said roll to permit the motor circuit switch to be placed in a closed position and stop the operation of the motor when said fingers are in lowered position within the said small apertures in the paper roll. 45

6. A device of the class described, having a hinged liftable toilet-seat, a hinged liftable metal plate adapted to rest on the top of the toilet-seat, a roll of paper revolvably mounted on the metal plate on one side of the toilet-seat, and a pulling 50 roller on said plate adapted to pull the roll of paper across the top of the toilet-seat when properly actuated, an actuating mechanism for operating the pulling roller, an electric motor circuit for the actuating mechanism and a magnet circuit for same, a coin-actuated mechanism adapted to operate the magnet circuit, means for operating the switch of the motor circuit, starting the actuating mechanism and the pulling roller, means operated by the roll of paper for holding the motor circuit switch in closed position, means in the actuating mechanism for opening the motor circuit switch and stopping the motor after a predetermined time, means in the toilet-seat for closing the magnet circuit a 65 second time when the toilet-seat is lifted, thus closing the motor circuit switch a second time and operating the pulling roller a second time, whereupon after a predetermined time the said means in the actuating mechanism for breaking the motor circuit again operates to stop the motor after its second period of operation.

7. A device of the class described, having a liftable toilet-seat, a liftable metal plate adapted to rest on the top of the toilet-seat, a roll of paper 75

- revolvably mounted on one side of the toilet-seat, a pulling roller adapted to pull the roll of paper across the top of the toilet-seat when properly actuated, an actuating mechanism for operating the pulling roller, an electric motor circuit for the actuating mechanism and a magnet circuit for same, a coin-actuated mechanism adapted to operate the magnet circuit, means for throwing in the switch of the motor circuit, starting the actuating mechanism and winding the pulling roller, means operated by the roll of paper for holding the motor circuit switch in closed position, means for opening the motor circuit switch and stopping the motor after a predetermined time, means in the toilet-seat for operating the magnet circuit when the toilet-seat is lifted, thereby closing the motor circuit switch and operating the motor and the roller a second time, whereupon after a predetermined time the said means in the actuating mechanism for breaking the magnet circuit and stopping the motor again operates after its second period of operation, and braking means in the actuating mechanism for bringing the motor to a positive stop during any period of its operation after the motor circuit has been disconnected.
8. A device of the class described, comprising a toilet-seat, a metal seat-cover therefor, a roll of paper wound on a roller adjacent to the one side of the toilet-seat, a second roller on the opposite side of the toilet-seat for winding the roll of paper thereon, and a coin-operated power actuating means for revolving the latter roller to advance the paper across the top of the toilet-seat, said means having a pivoted armature mounted therein and an electric motor, an electric circuit for operating said actuating means, braking means for the said actuating means comprising: a pintle mounted therein, a depending member pivotally mounted on the same, a horizontal brakeshoe, pivotally connected to the depending member, a link-bar pivotally connected to the brakeshoe and to the armature of the actuating mechanism, and a horizontal disc on the motor adapted to be engaged by the brakeshoe for positively stopping the actuating mechanism after the electric circuit operating same has been disconnected therefrom.
9. A device of the class described comprising a toilet-seat, a metal seat-cover therefor, a roll of paper adapted to slide over the metal seat-cover, having alternately therein an apertured open space, and a portion of paper, a pair of opposed strips of tape mounted on the paper of the roll, providing a means of drawing the roll across the toilet-seat, a roller at one side of the toilet-seat on which the roll of paper is primarily mounted, a second roller mounted on the opposite side of the toilet-seat for drawing the roll of paper forward, a coin-actuated power-actuating mechanism for revolving the last-named roller, comprising an electromagnet, an armature for said magnet, a motor having a stem, a worm on said stem, a worm-gear in meshed engagement with the worm, a pintle on which the worm-gear is mounted in engagement with the winding roller of the paper roll, an electric circuit for operating the actuating mechanism, a coin-actuated mechanism electrically connected with the electro-magnet for operating the latter, and means for starting the motor connected with the armature of the electro-magnet, means cooperating with the roll of paper for stopping the motor and for releasing the armature from the electro-magnet and returning said armature to its normal

position at a distance from the magnet, a braking means for positively stopping the motor, after the electric motor circuit has been broken, comprising: a pintle mounted in the actuating mechanism, a depending member, a link-bar pivotally connecting the brakeshoe and the armature, and a horizontal disc mounted on the motor adapted to be engaged by said brakeshoe.

10. A roll of paper for a toilet-seat, comprising a pair of opposed continuous longitudinal tape members on which are periodically mounted successive sheets of paper, each of which is provided with a pair of opposed small apertures at each end thereof, and a large centrally disposed aperture adapted to fit over the central opening of a toilet-seat.

11. In a device for operating the downwardly projecting rod of a coin-actuated mechanism, a horizontally disposed pintle, a worm-gear rigidly mounted thereon, a drum mounted on the pintle, a large diameter disc loosely mounted on said drum having a concentric slot formed therein adjacent to its perimeter, a small diameter disc rigidly mounted on said drum, a pair of opposed pointed bars mounted on the face of the large diameter disc, a bolt having a head thereon in engagement with the side of the large diameter disc, which passes through the concentric slot in said disc, and is rigidly mounted in the worm gear, a coil spring on the drum located between the two discs, having one end rigidly secured in the small disc and its other end connected to the aforesaid bolt, the smaller disc being designed to operate with the rotation of the pintle and drum and the larger disc being designed to operate only after the aforesaid bolt has travelled the length of the concentric slot formed in the said larger disc, and resilient means mounted on the pintle for holding the worm gear and said drum in pressed relation to each other.

12. In a device for revolving a roller, a roller having a circular slot formed in the end of same and a pair of diametrically opposed auxiliary slots connected to the circular slot, a pintle having a pair of opposed lugs on the end of same adapted to engage with the auxiliary slots of the roller, a worm-gear on the pintle, an abutment in engagement with the end of the roller, a sleeve on the pintle mounted in said abutment, a drum on the pintle, a small diameter disc mounted on said drum, a larger diameter disc loosely mounted on said drum having a concentric slot formed therein, a pin having a head in engagement with the side of the large disc, mounted in the worm-gear and operating in the slot of the larger disc, a coil spring surrounding the drum having one end rigidly attached to the small disc and its other end secured on said pin, resilient means on the pintle for holding the worm-gear, the drum, the sleeve and the abutment in close relation to each other, said pintle, drum and discs being adapted to permit the withdrawal of the pintle with its outstanding lugs from the slots formed in the end of the roller, and said apparatus being designed to revolve the large diameter disc after the pin mounted in the worm-gear has travelled the length of the concentric slot in the larger disc.

13. In an actuating mechanism having a rear wall therein, a motor having a stem there-through, a worm on the motor stem, a worm-gear in engagement with said worm, a pintle mounted in said rear wall on which the worm-

- gear is mounted, a drum on the pintle, a large diameter loosely mounted disc, on said drum having a pair of opposed pointed bars rigidly mounted thereon, means for revolving the large 5 diameter disc when the drum is revolved, a coin-actuated mechanism having a downwardly projecting rod thereon for operating same, a pin mounted in the rear wall, a coil spring depending therefrom, a second pin mounted in the 10 rear wall of the actuating mechanism, an outstanding bracket revolvably mounted on the said pin, having its outstanding leg connected with the said depending coil spring, an L-shaped member rigidly connected with said bracket and 15 adapted to engage the downwardly projecting rod of the coin-actuated mechanism and release a coin therefrom when the pointed bars of the aforesaid large diameter disc engage the leg of the outstanding bracket and overcome the 20 strength of the spring connected with said bracket, a bent plate on the bracket pin, and an outstanding pin mounted on the rear wall of the actuating mechanism in engagement with said bent plate and forming a stop therefor.
- 25 14. In an apparatus for dispensing toilet-seat covers, a toilet-seat, a pair of opposed tapes, a plurality of successive portions of paper spacedly mounted on said tapes, forming a roll therewith which is adapted to slidably operate over the 30 toilet-seat, and which has comparatively large open spaces between the said paper portions thereof, for the purpose of leaving the toilet-seat periodically uncovered, and roll advancing means, for the purpose of alternately advancing 35 the paper portions of the roll and the open-space portions thereof, over the toilet-seat.
15. A device of the class described, having a toilet-bowl, and comprising a toilet-seat liftably mounted on the bowl, provided with a central 40 opening therein, a pair of opposed tapes, a number of successive portions of paper mounted on said tapes and forming a roll therewith, each paper portion having a central opening therein adapted to register with the opening in the said seat, and spaced apart from each other on said 45 roll, for the purpose of periodically leaving the toilet-seat fully uncovered, actuating means for first advancing a paper portion of the roll over the central opening of the seat, and means actu-
- ated by the toilet-seat when lifted from the bowl for operating the roll advancing means and placing an open-space portion of said roll over the central opening of the toilet-seat.
16. In a device of the class described, having a 5 toilet-bowl, a pair of opposed tapes, a plurality of a liftable toilet-seat superimposed on the bowl, a pair of opposed tapes, a plurality of successive spaced-apart paper portions mounted on said tapes forming a continuous roll having 10 interstices between each paper portion, of sufficient dimensions to expose the full top of the seat when the intersticed portions are drawn over said seat, coin-controlled power means for placing the paper portions of the roll directly over the top 15 of the toilet-seat, and means actuated by the toilet-seat when lifted from the bowl, for operating the power means for the purpose of removing the used paper portions of the roll from the seat, and for placing the intersticed portions 20 of the roll over said toilet-seat.
17. In a device of the class described, provided with a toilet-bowl, a liftable toilet-seat mounted over the bowl, a pair of parallel longitudinal tapes, a number of successive portions of paper 25 spacedly mounted on said tapes forming a roll therewith adapted to be drawn over the toilet-seat, and having large interstices therein adapted to expose the whole toilet-seat, when the intersticed portions of the roll are drawn over the 30 toilet seat, means for automatically raising the toilet-seat from the bowl, means for advancing the paper portions of the roll to superimposed position directly over the toilet-seat, and means actuated by the toilet-seat when the same is 35 lifted from the bowl, for operating the roll advancing means, for the purpose of removing used paper portions of the roll, and drawing intersticed portions thereof to superimposed position over the toilet-seat.
18. A roll for use in connection with a device 40 of the class described, comprising a pair of opposed tapes, and a number of successive spaced-apart paper portions mounted on said tapes, each having a central opening therein, and said paper portions forming interstices between them, which expose the whole toilet-seat as the roll is advanced over the said seat.

WILLIAM ELRICK.
